UNITED STATES PATENT OFFICE.

JOHN C. IVES, OF WATERBURY, CONNECTICUT.

DESIGN FOR A MOVABLE JAW FOR WRENCHES.

SPECIFICATION forming part of Design No. 27,575, dated August 24, 1897.

Application filed February 25, 1897. Serial No. 625,054. Term of patent 7 years.

To all whom it may concern:

Be it known that I, JOHN C. IVES, a citizen of the United States of America, residing at Waterbury, in the county of New Haven and State of Connecticut, have invented and produced a new and original Design for Wrenches, of which the following is a description, reference being had to the accompanying drawings.

10 In the drawings, Figure 1 is a side elevation of this design for the movable jaw of a wrench, and Fig. 2 is a perspective view of the same.

As shown in said drawings, the leading feature of my design consists in the specific configuration of the movable jaw of a nut-wrench.

Referring thereto by letter, *a* designates the jaw complete, which consists of a body whose front edge *b* is straight and vertical, 20 whose upper edge has a U-shaped cut-out *c*, leaving two arms *c'*, which are pierced longi-

tudinally, as at *d*, for the reception of the bar of the wrench-arm, whose rear edge *r* is also straight and vertical and whose lower edge is formed on an ogee curve *o*, extending from the rear edge *r* to and into a straight and flat portion *f*, which in turn extends into the lower portion of the front edge at *l*, where it joins the same in a right angle.

The whole may be chased, engraved, or ornamented in any suitable manner, and it is obvious that this jaw will form an ornamental portion of a nut-wrench. It is pleasing to the eye.

What is claimed as new is—

The design for the movable jaw of a wrench, substantially as herein shown and described.

JOHN C. IVES.
